UNITED STATES PATENT OFFICE.

GEORGE E. CURTISS, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A JUG.

Application filed July 16, 1924. Serial No. 10,165. Term of patent 14 years.

To all whom it may concern:

Be it known that I, GEORGE E. CURTISS, a citizen of the United States, residing at New Britain, county of Hartford, and State of Connecticut, have invented a new, original, and ornamental Design for Jugs, fully described and represented in the following specification, and the accompanying drawings, forming a part of the same.

The drawing is a view in side elevation of a jug showing my new design.

What is claimed is:

The ornamental design for a jug, as shown.

In testimony whereof, I have hereunto set my hand.

GEORGE E. CURTISS.
